UNITED STATES PATENT OFFICE.

JOSIAH ROSS, OF BUFFALO, NEW YORK.

DRILLING-MACHINE.

SPECIFICATION forming part of Letters Patent No. 441,900, dated December 2, 1890.

Application filed September 19, 1890. Serial No. 365,477. (No model.)

To all whom it may concern:

Be it known that I, JOSIAH ROSS, a citizen of the United States, residing at Buffalo, in the county of Erie and State of New York, 5 have invented new and useful Improvements in Drilling-Machines, of which the following is a specification.

This invention relates to a drilling-machine in which the drill-spindle is journaled in a feed-screw, whereby the drill is moved toward and from the bed-plate. In drills of this character as heretofore constructed the entire thrust of the drill was brought to bear against the lower side of the feed-screw, which caused 15 this part to wear rapidly from the intense friction and necessitated the employment of heavy washers, which required to be frequently renewed.

The object of my invention is to overcome 20 this difficulty; and it consists to that end of a ball-bearing which is interposed between the drill-spindle and the feed-screw, thereby relieving these parts from excessive friction and wear, and enabling the drill to rotate with greater freedom and to be run with less power.

In the accompanying drawings, Figure 1 is 25 a fragmentary sectional elevation of a vertical drilling-machine provided with my improvements. Fig. 2 is a sectional elevation of the ball-bearing on an enlarged scale. Fig. 3 is a horizontal section in line $x-x$, Fig. 2.

Like letters of reference refer to like parts in the several figures.

35 A represents the main frame of a vertical drilling-machine, and a the horizontal bed-plate formed with or secured to the main frame.

B represents the bit or drill, which is secured in the socket b at the lower end of the vertical spindle C in the usual manner. The lower portion of the drill-spindle is journaled in a hollow feed-screw D , which latter is arranged in a screw-threaded socket or opening 45 d , formed at the outer end of an arm e of the main frame. The upper portion of the drill-spindle is arranged to slide vertically through the hub of a bevel gear-wheel E , which latter is journaled in a bearing f , arranged in a projecting arm of the main frame. The bevel-gear E is free to turn in its bearing, but is

held against vertical movement by means of shoulders h , formed on its hub and abutting against opposite sides of the bearing. The drill-spindle is compelled to rotate with the 55 bevel-gear E by means of a key i and key-groove formed in the gear-hub and the spindle, but is capable of sliding lengthwise in the hub of the gear-wheel in a well-known manner. A rotary motion is imparted to the 60 drill-spindle by a bevel-gear G meshing with the gear-wheel of the spindle, but it may be operated in any other suitable manner.

J represents an annular shoulder formed on the spindle above the drill-socket, and j is 65 a ring or washer surrounding the spindle, resting on said shoulder and forming the lower part of the ball-bearing. The upper side of said ring is provided with an annular channel or groove k , in which an annular row 70 of hardened steel balls of suitable diameter are arranged.

L represents another ring or washer surrounding the spindle, bearing upon the upper side of the balls and forming the upper 75 part of the ball-bearing. The upper ring is provided in its lower side with an annular groove l , in which the balls are seated. An annular depending flange l' is preferably formed on the upper ring, which flange overlaps the lower washer and excludes dust and dirt from the ball-bearing. The lower end of the feed-screw bears against the upper washer, while the upper end of the feed-screw bears against a collar m , secured to the spindle, 85 whereby the latter is compelled to move vertically with the feed-screw. Upon feeding the screw downwardly by means of the hand-wheel n when the drill rotates the drill is forced down upon its work through the medium of the ball-bearing, which latter permits a powerful pressure to be brought on the drill without excessively wearing the parts. It also reduces the friction considerably, permitting the drill to rotate more freely under 95 the varying strains to which it is subjected and enabling it to be operated with less power.

This ball-bearing is very simple in construction, having but few parts, which can be easily renewed at moderate expense.

I claim as my invention—

1. In a drilling-machine, the combination,

with the spindle and the feed device, of a ball-bearing interposed between said spindle and the feed device, substantially as set forth.

2. The combination, with the feed-screw and the spindle journaled in the feed-screw and having a shoulder, of a ball-bearing interposed between said feed-screw and the shoulder of the spindle, substantially as set forth.

3. The combination, with the drill-spindle having an annular shoulder, of a lower grooved washer resting on said shoulder, an annular row of balls arranged in said groove,

an upper washer resting on said balls and provided with a marginal flange which overlaps the lower washer, and a feed-screw surrounding the spindle and bearing upon the upper washer, substantially as set forth. 15

Witness my hand this 10th day of September, 1890.

JOSIAH ROSS.
